UNITED STATES PATENT OFFICE.

ABRAHAM J. SCHULTZ, OF NEWARK, NEW JERSEY, ASSIGNOR TO COLONIAL STAMPING COMPANY, INC., A CORPORATION OF NEW JERSEY.

MOUNTING NAPS OR CAPS FOR POSTS, POLES, OR RODS.

1,422,226.

Specification of Letters Patent.

Patented July 11, 1922.

Application filed August 13, 1920. Serial No. 403,434.

To all whom it may concern:

Be it known that I, ABRAHAM J. SCHULTZ, a citizen of the United States, residing at Newark, in the county of Essex and State 5 of New Jersey, have invented certain new and useful Improvements in Mounting Naps or Caps for Posts, Poles, or Rods; and I do hereby declare the following to be a full, clear, and exact description of the invention, such as will enable others skilled in the art to which it appertains to make and use the same, reference being had to the accompanying drawings, and to characters of reference marked thereon, which form a part 10 of this specification.

This invention relates, generally, to improvements in the attachment of naps, caps, top-mounts, or knobs to ends of hollow or tubular bed-posts, curtain-rods, and the like; 20 and, the present invention has reference, more particularly, to a novel means and method of securing naps, caps, top-mounts, knobs, or the like, upon the ends of hollow or tubular elements, such as bed-posts, curtain or portière-rods, or the like, with a view 25 of providing a self-locking nap, cap, top-mount, or knob, which is simply pushed into position over the end of the hollow or tubular element, and retained in a positively fixed 30 and non-detachable relation to the end of the said hollow or tubular element.

The invention, therefore, has for its principal object to positively unite by means of a self-locking means ornamental naps, caps, 35 top-mounts, knobs, or the like, over the ends of hollow or tubular elements, such as metal bed-posts, curtain poles and other rods, in a most efficient and simple manner, without 40 the use of the usual pin-screws, or rivets, or without soldering, at the same time providing 45 a method by means of which the various elements mentioned are readily and quickly united, at a considerable reduction in the cost of manufacture, and in a most effective manner.

In the practice of mounting naps, caps, top-mounts, knobs, or the like over the ends 50 of hollow or tubular posts, poles, or rods, as at present, the sheet-metal naps, caps, top- 55 mounts, knobs, or the like, are slipped over the ends of such posts, poles, or rods, and are then secured in place by means of pin-screws, which, it has been found in practice, soon work loose, and often are lost, thus leaving 60 the closing ornament in an unsecure posi-

tion upon the end of the post, pole or rod, with the possibility of the loose ornament working off and also becoming lost. In some instances the said end ornaments are riveted or soldered to the ends of the posts, poles, or rods, but this entails a tedious operation, with considerable cost in the manufacture, all of which is desirable to avoid; and, the invention has for its further object to provide a self-locking nap, cap, top-mount, knob, or 65 the like, which by being secured over the end of the hollow or tubular post, pole, or rod in the manner hereinafter more fully set forth, overcomes the objectionable features mentioned in the above.

Other objects of the present invention not hereinbefore enumerated will be clearly understood from the following detailed description of the same.

With the various objects of the present invention in view, the said invention consists, primarily, in the novel nap, cap, top-mount or the like for hollow or tubular posts, poles or rods, hereinafter set forth; and, the present invention consists, furthermore, in 75 the novel means and method of uniting the nap, cap, top-mount, knob, or the like in its fixed position upon the end of a hollow or tubular bed-post, curtain-pole, rod, or the like, and in the novel arrangements and combinations of the various devices and parts, as well as in the details of the construction 80 of the said parts, all of which will be more fully described in the following specification, and then finally embodied in the clauses of 85 the claims which are appended to and which form an essential part of the said specification.

The present invention is clearly illustrated in the accompanying drawings, in which:— 95

Figure 1 represents in elevation a fragmentary portion of the usual tubular or hollow metal bed-post and an ornamental nap or cap mounted and secured thereon according to the principles of the present invention. 100 and Figure 2 is a transverse vertical sectional representation of the said ornament nap or cap, with a portion of the bed-post shown in elevation, and a part of the upper end of the said post represented broken away, to 105 illustrate more particularly the securing or holding means with which the nap or cap is provided to positively secure the same upon the end of the post.

Figures 3 and 4 are detail sectional repre- 110

sentations of fragmentary portions of tubular posts and ornamental naps or caps, said views illustrating slight modifications of the fastening means for securing ornamental 5 naps or caps upon the ends of posts.

Similar characters of reference are employed in the said above described views, to indicate corresponding parts.

Referring now to the several figures of the 10 drawings, the reference-character 1 indicates an end-portion of a hollow or tubular metal bed-post, or the like, upon which is mounted and secured an ornamental nap or cap, according to the principles of the 15 present invention. The nap or cap, as shown in Figure 2 of the drawings, usually comprises the main ornamental body or member 2, the lower portion of which is formed with a throat 3, the opening of 20 which is of the same cross-sectional area as that of the post 1, so as to be readily slipped over the end of the post, as will be clearly evident. As indicated in the drawing, the upper and outwardly flaring 25 portion 4 of the said body or member 2 is bounded by an upwardly extending rib or projection, as 5, terminating in a laterally extending annular element, as 6. Extending upwardly from said annular element 6, is an 30 annular flange-like element, as 7, said element 7 providing a collar about which is fitted the annular flange-like portion 9 of an ornamental closing top or element 8. The said top 8 is secured in place by means 35 of the inwardly turned marginal edge 10 of the said flange-like portion 9, the said marginal edge 10 being securely forced or pressed into the annular off-set which is formed by the annular elements 5 and 6, as 40 will be clearly evident from an inspection of Figures 2, 3 and 4 of the drawings.

Referring now more particularly to Figure 2 of the drawings, suitably fitted within the annular flange-like element 7 is a post- 45 receiving and nap or cap-seating element comprising a member 11 formed with an annular off-set 12 for seating upon the corresponding off-set portion formed by the annular elements 5 and 6. Extending down- 50 wardly and inwardly from said annular off-set 12 is a base-member 13, which is marginally curved, as at 14, and then extended annularly, upwardly and outwardly, as at 55 15, the upper marginal edge-portion of the member or portion 15, having an inwardly extending flange 16. These parts, as will be seen from an inspection of said Figure 2, provide a stop-member having a receiving chamber in which the upper end-portion 60 of the said post 1 is inserted and fitted against the said flange 16 which serves as a stop, as will be understood.

That the said ornamental nap or cap thus provided will be positively and securely fas-

tened upon the end-portion of the post 1 65 to prevent a loose fit and to guard against any displacement of the nap or cap from the end of the post, the diameter across the marginally curved portion 14 being slightly less than the diameter across the post 1, 70 so that when the nap or cap is fitted over the end of the post, these parts will bind or be in frictional contact. In addition to this frictional contact, when the nap or cap is forced home over the end-portion of the 75 post 1, the annular marginally curved portion 14 of the base-member 13 is made with a multiplicity of serrations, sharp projections, or other biting elements, as 17, which securely imbed themselves in the outer surface-portions of the inserted end of the post 1, whereby the said ornamental nap or cap is securely fastened and seated in its position upon the end of the post, against a loose fit or accidental displacement. 80

In lieu of the form of stop-member of the post-receiving and nap or cap-seating element just described in connection with said Figures 1 and 2 of the drawings, having merely the inwardly extending flange 16, 90 against which the end of the post 1 is brought, the said flange 16, as will be seen from Figures 3 and 4, may be provided with an additional member 18, in the form of a vertically disposed annular collar, said 95 collar providing with the flange 16 and the member or portion 15, an annular receiving chamber 19, for the reception of the end of the post 1.

In said Figure 3, instead of providing 100 the marginal curved portion 14 with a multiplicity of serrations, sharp projections, or biting elements, the said vertically disposed annular collar 18 is provided with a multiplicity of serrations, sharp projections, 105 or biting elements, as 20, which extend into the post-receiving chamber 19, to engage the interior surface-portion of the post in holding or retaining contact, as will be clearly understood from an inspection of said Figure 3 of the drawings. 110

In some cases, if desired, a multiplicity of serrations, sharp projections, or biting elements, as 21 and 22, may be disposed upon the marginal curved portion 14 and 115 also upon the said annular collar 18, respectively, said serrations, sharp projections, or biting elements 21 and 22 projecting into the post-receiving chamber 19, so as to engage both the outer and interior surface- 120 portions of the post 1 in holding or retaining contact with said post when the latter is inserted into the chamber 19, as will be readily understood from an inspection of said Figure 4 of the drawings. 125

From the foregoing description of my present invention, and from an inspection of the several figures of the drawings, it will

be clearly seen, that the various parts are easily and quickly brought into their assembled and positively united relation, without the use of pin-screws, rivets, or solder, as 5 heretofore, so that thereby the parts are more quickly united, and the cost of the manufacture greatly reduced, because the uncertain operation of inserting a clinching or riveting tool within the assembled 10 tubular or hollow members is clearly avoided.

I am aware, therefore, that some changes may be made in the arrangements and combinations of the various devices and parts, as well as in the details of the construction 15 of the same, without departing from the scope of the present invention as described in the said specification, and as defined in the clauses of the claims which are appended to the said specification. Hence, I do not 20 limit my present invention to the exact arrangement and combinations of the various devices and parts as described in the said specification, nor do I confine myself to the 25 exact details of the construction of the said parts as illustrated in the accompanying drawings.

I claim:—

1. In combination with an element, as a metal bed-post, rod or pole, an ornamental 30 nap, and an interiorly disposed seating element provided with a central open portion, said seating element having a stop-member surrounding said opening and provided with a chambered portion for the reception of the 35 end-portion of said post, rod or pole, said chambered portion comprising an annular wall, and a multiplicity of biting serrations connected with and extending from said wall, said serrations being adapted to be 40 forced into holding engagement with said post, rod or pole, when the end-portion of the same is inserted in the chambered portion of said stop-member.

2. In combination with an element, as a 45 metal bed-post, rod or pole, an ornamental nap comprising a hollow body, and a seating element within said body, said seating element comprising a base-member formed with a centrally disposed marginal curved 50 portion, an annularly disposed wall extending upwardly from said curved portion, and an annular stop-flange projecting inwardly from said wall, all arranged and constructed to provide a chamber for the reception of 55 the end-portion of said post, rod or pole, and a multiplicity of biting serrations connected with and extending from said marginal curved portion adapted to be forced into holding engagement with said post, rod

or pole, when the end-portion of the same is 60 forced into said chamber.

3. An ornamental nap comprising a hollow body and a seating element extending transversely across said body, said seating element comprising a base-member formed 65 with a centrally disposed marginal curved portion, an annularly disposed wall extending upwardly from said curved portion, an annularly disposed stop-flange projecting inwardly from said wall, and a multiplicity 70 of biting serrations connected with and extending from said marginal curved portion.

4. An ornamental nap comprising a hollow body provided within said body with an annular seating element, said annular element being provided with a centrally disposed post-receiving opening surrounded by an annular wall, said wall having multiplicity of biting serrations. 75

5. An ornamental nap for a metal bed- 80 post, rod or pole, comprising a chambered cap formed with a downwardly and inwardly flaring tubular post-receiving member, said member at its free end having a post-engaging throat, combined with an auxiliary post-receiving element disposed and marginally secured within said chambered cap, said auxiliary post-receiving element 85 having a centrally disposed opening in alignment with the throat of said cap, for the reception of a post and retention of the nap upon the post by a biting action of the marginal edge bounding the central opening of said auxiliary post-receiving element. 90

6. In combination with a hollow element, 95 as a metal bed-post, rod or pole, an ornamental chambered cap formed with a downwardly and inwardly flaring tubular post-receiving member, said member at its lower end having a post-engaging throat, and an independent auxiliary post-receiving element within said chambered cap and marginally secured thereto, said auxiliary post-receiving element having a centrally disposed open portion in alignment with said 100 post-receiving throat, for the reception of a post and retention of the nap upon the post by a biting action of the marginal edge bounding the central opening of said auxiliary post-receiving element. 105

In testimony, that I claim the invention set forth above I have hereunto set my hand this 11th day of August, 1920.

ABRAHAM J. SCHULTZ.
